UNITED STATES PATENT OFFICE.

JACOB I. GLICKERMAN, OF CHICAGO, ILLINOIS.

SEALING-STRIP-SOLDERING GUIDE.

1,312,318.

Specification of Letters Patent. Patented Aug. 5, 1919.

Application filed July 18, 1918. Serial No. 245,579.

To all whom it may concern:

Be it known that I, JACOB I. GLICKERMAN, citizen of the United States, residing at Chicago, in the county of Cook and State of Illinois, have invented certain new and useful Improvements in Sealing-Strip-Soldering Guides; and I do hereby declare the following to be a full, clear, and exact description of the invention, such as will enable others skilled in the art to which it appertains to make and use the same.

My invention relates to appliances for facilitating and expediting the attaching of metal bands or banding strips to metal objects, its general object being to provide simple and easily manipulated means for holding both the object and the banding or banding strip in proper relation to each other while joining them by soldering, brazing or welding.

With certain kinds of shells, such as the so-called anti-aircraft shells, it is customary to protect the fuse of the shell from moisture and from foreign matter by employing a metal cap which is placed over the tip of the shell and which is connected to the casing of the shell by a manually detachable strip or band which forms a hermetic seal between this cap and the casing of the shell. For this purpose, it is customary to use a metal strip somewhat longer than the circumference of the adjacent annular portions of the cap and the casing, thereby affording a projecting tip which may be grasped between the fingers when the strip is to be ripped off, so as to detach the cover. In manufacturing the parts, this strip is commonly attached first to the mouth of the cap by means of soft solder, and is afterward soldered to the corresponding part of the casing of the shell. In attaching such strips to the caps, it is important that the strip should be held closely against the proper part of the cover during the soldering operation, and that it should occupy a substantially cylindrical position, so as to afford the desired close approach to the mouth of the shell casing when it is affixed to the latter. In practice, this has been found difficult owing to the resiliency of the metal and the consequent tendency of the strip to uncoil or spring away from the portion of the cover to which it is to be affixed, so that the attaching of these strips to the caps has proven to be quite a slow and expensive operation.

In one of its important applications, my

invention aims to provide simple means for holding such a cover in convenient working position, for rapidly disposing the banding strip in the desired position with respect to such a cover, for holding the two elements in this desired relation while they are being soldered or otherwise affixed to each other, and for readily permitting the withdrawal of the resulting composite article. Still further objects will appear from the following specification and from the accompanying drawings in which—

Figure 1 is a fragmentary elevation of the upper end of a shell having a fuse-protecting cap fastened to it after the manner for which the device of my invention is intended.

Fig. 2 is a perspective view of the cover of the shell of Fig. 1, with the metal sealing strip attached thereto and ready for soldering the latter to the neck of the shell casing.

Fig. 3 is a perspective view showing the holder of my invention as slipped upon a metal fuse-protecting cover prior to the insertion of the metal banding strip.

Fig. 4 is an end view of the collar or holder of my invention as it appears when both the fuse cover and the metal strip are in position, ready for being soldered to each other.

Fig. 5 is an enlarged and fragmentary section taken longitudinally through the parts of Fig. 4 showing the manner in which an edge portion of the sealing strip is positioned between the contracted neck of the cover and the contracted portion of the bore of the collar.

Fig. 6 is a fragmentary plan view of the metal sealing strip shown as attached to the cover in Fig. 2.

While my invention in its general objects may obviously be applied to other purposes besides the specific one in connection with the one I am illustrating and describing, its principles may be seen from such a particular example. In this case, the problem so expeditiously solved by means of my invention is that of securing a metal strip in the form of a substantially cylindrical band around the contracted neck 2 of a shell cover 3, with the resulting band disposed in substantially cylindrical formation, so that it can readily be soldered to the cylindrical neck of the casing 4 of a shell. For use in this connection, my invention desirably

consists of a collar 5, preferably made of metal and having a bore having two different diameters connected by an annular shoulder. The larger bore is of such diameter as to snugly fit the portion 6 of the cap which is above the contracted neck 2 of the cap, so that this portion will be held by friction in the collar when inserted as shown in Fig. 5. The other end of the bore of the collar is contracted as shown in Fig. 5 to a diameter somewhat greater than the outside diameter of the neck 2 of the cover, the difference in diameter being slightly more than twice the thickness of the banding strip 1 which is to be fastened to the cover. This strip 1 desirably has one end beveled as shown in the drawings, so as to afford a sharp end which may be easily inserted between the portion of the neck 2 and the adjacent portion of the collar 5, after which the strip or band may be inserted around the remainder of the periphery of the neck 2, the surplus length (including the narrow tip 7 of the strip) being inserted between the pointed end portion of the strip and the adjacent bore of the collar. Owing to the natural resiliency of the metal, the strip when thus disposed will tend to spring outwardly against the bore of the collar, thus holding itself in place by friction even if variations in the size of the metal parts should be such that the strip is not tightly clamped between the neck of the cover and the collar. In either case, the strip will thus be held in a substantially cylindrical formation and with one edge portion overlapping the neck 2 of the cover, so that the strip can readily be secured to this cover by running a soldering iron along the end of the neck of the cover. Or, the strip may be secured to the cover when in this position by any other suitable method, as for instance by brazing or by electric welding.

When the two metal parts have thus been secured to each other, the collar can easily be removed by merely sliding it off, thus leaving the metal band securely attached to the cover as shown in Fig. 2. By suitably proportioning the diameter of the larger end of the bore of the collar, I can cause the narrow end of the metal strip to be clamped so tightly between the collar and the other end of the metal strip, that the solder applied from the interior of the band will not enter materially between the overlapping end portions of the strip. Consequently, the

narrow tip 7 of the strip will be left free to spring outward or tangential of this band when the collar is removed, thereby affording a ready finger-hold for the manual detaching of the strip later on.

In practice, I have found that even an unskilled helper can soon learn to slip both the cover and the metal strip into their proper positions by means of the holder of my invention with more certainty and in a very much shorter time than has been possible by the methods heretofore in use. Moreover, when thus assembled, the parts are held in proper position, so that there is no danger of their gaping or springing apart, or otherwise shifting their relative position during the soldering. Consequently, I not only secure a decided saving in time, but also reduce the spoilage. Moreover, since my holder involves no screws or other movable parts, there is nothing about it to get out of order, so that it is not only cheaply manufactured, but also exceedingly durable. Likewise, by slightly varying the diameters of the two portions of the bore I can readily adapt the holder of my invention to different thicknesses of metal and to different sizes of the neck or annular portion to which the metal strip or band is to be attached.

However, while I have described my invention as used in connection with shell covers, and as embodying a collar of substantially cylindrical exterior, I do not wish to be limited to this particular use of my invention, nor to the particular shape of holder or other details of the construction and arrangement hereby shown or described, it being obvious that the same might be varied in many ways without departing from the spirit of the appended claim.

I claim as my invention:

An appliance for holding bands in soldering relation to reduced cylindrical necks of bodies comprising a one-piece collar having major and minor bore portions, the former snugly receiving the body and the latter the neck, the diameter of the minor portion being sufficiently in excess of the neck to afford a space to receive and frictionally hold the band with the ends thereof overlapped whereby one end is left free after the soldering operation to form a hand hold to permit subsequent ripping of the band.

Signed at Chicago, Illinois, July 11th, 1918.

JACOB I. GLICKERMAN.
